WILLIAM A. READE, OF CLEVELAND, OHIO, ASSIGNOR TO LUDLOW TYPOGRAPH COMPANY, OF CLEVELAND, OHIO, A CORPORATION OF MAINE.

TYPE-BAR OR CASTING-SLUG.

1,241,019.

Specification of Letters Patent. Patented Sept. 25, 1917.

Original application filed May 24, 1911, Serial No. 629,099. Divided and this application filed July 3, 1914. Serial No. 848,764.

To all whom it may concern:

Be it known that I, WILLIAM A. READE, a citizen of the United States, and a resident of Cleveland, county of Cuyahoga, and State of Ohio, have invented a new and useful Improvement in Type-Bars or Casting-Slugs, of which the following is a specification, the principle of the invention being herein explained and the best mode in which 10 I have contemplated applying that principle, so as to distinguish it from other inventions.

The present improved type bar or casting slug is shown and described in my co-pending application for typograph mechanism filed May 24, 1911, Serial No. 629,099 out of which the present case has been required to be divided. While the aforesaid typograph mechanism, which is of necessity shown and 20 described in the present specification also, is particularly adapted for the making of type bars or slugs of the kind in question, it will be understood that other mechanism suitable for the purpose may be devised, no limitation being implied to the production of such 25 bars or slugs by any particular typograph mechanism.

It should furthermore be noted that the method of making type-bars or slugs exemplified in the operation of the aforesaid mechanism, and resulting in the production of the aforesaid bars or slugs, forms the subject matter of a separate divisional application filed by me March 1, 1917, Serial No. 35 151,715.

As will be readily understood, larger type than are found on the matrix bars regularly used on typographs are very frequently desired for printing headlines and advertisements, and the object of the mechanism herein described is to do away with the necessity for maintaining a stock of "sorts" in order that the printer may be able to set up a form with such larger type, since with such mechanism including a single font of matrices of such larger type, any amount of large type matter may be set up.

I am aware that it has heretofore been sought to cast slugs with initial letters 50 larger than the body face by simply allowing the matrix of the larger letter or other character to over-lap the front face of the mold. The slug thus formed will have a thin over-lapping body of metal bearing

such larger character on its face, which 55 over-lapping portion is adapted to extend over the face of an adjacent smooth slug. Although such extended character may be thus supported from below, it is nevertheless so thin that it has a tendency to curl, especially on cylinder presses and when subject to hard usage. One object of the present invention, accordingly, is the avoidance of the difficulty just noted, by providing a slug 60 fully as strong and durable as the original 65 one, of uniform thickness throughout. A further object of the invention is to produce slugs by means of which a line of large 70 type of greater length than the normal width of a column may be set up without any breaks occurring between successive slugs. To the accomplishment of this and related ends, said invention, then, consists of the means hereinafter fully described and particularly pointed out in the claims. 75

The annexed drawing and the following description set forth in detail certain mechanism embodying the invention, such disclosed means constituting, however, but one 80 of various mechanical forms in which the principle of the invention may be used.

In said annexed drawing:

Figure 1 is a transverse section through a mold and the adjacent parts of a typograph 85 adapted to produce my improved type bar or casting slug; Fig. 2 is a perspective view of an improved matrix bar that forms a feature of such mechanism; Fig. 3 is a similar view of a blank matrix bar for use in conjunction with the foregoing; Fig. 4 is a perspective view of a slug, or line of type, cast 90 with matrix bars of the kind just referred to; Fig. 5 is a transverse sectional view of an assembled body of such slugs; Fig. 6 illustrates a modification in construction; Fig. 7 is a section of the slugs produced thereby; Fig. 8 is a longitudinal section through the mold illustrating the manner in which a slug such as shown in Fig. 4 may 95 be cast; Fig. 9 is a similar but broken longitudinal sectional view through the mold illustrating the manner in which a different form of slug may be cast; and Fig. 10 illustrates several forms of slugs. 100

As indicated in the above brief description of the drawing, the parts more immediately affected by the present improvement are the mold and matrix bars which 105

coöperate to form the slug or line of type. The form of mold 1 appearing in Fig. 1 is that employed in the so-called Ludlow typograph and is shown in association with the 5 supporting bed 2. The latter may be regarded simply as typical of any suitable support whereon the matrix bars 3 are adapted to rest pending the approach to the mold of the nozzle 4 of the casting pot (not 10 shown), from which molten metal is designed to be supplied to the mold from beneath. The usual terminal "squirt plate" 5 closes the end of the nozzle and directly contacts with the mold, as will be readily 15 understood.

For the casting of slugs of the kind under consideration, the matrix bars 3 each have a matrix of only a single character, and are correspondingly shorter than the longer bars 20 of the Ludlow typograph whereon a number of matrices are regularly provided. These short matrix bars are furthermore distinguished from short bars heretofore employed in other constructions of typograph, 25 by being more or less deeply recessed on their under faces and having the matrices 6, proper, located at the bottoms of these recesses 7 (see Fig. 2). The recesses in question provide for the formation of a slug 8 30 with an upper overhanging portion 9 of corresponding dimensions, when a body of such matrices are assembled, as will be readily understood.

The manner in which the matrices are 35 thus assembled and held in place during the casting operation is a matter of indifference; a simple frame 10, preferably of rectangular form, is shown, in the drawing, while a presser foot 11 is employed to clamp bars 3 40 against the casting face of the mold. For forming the spaces between words, as also for leaving blank spaces at the ends of the line where the type matter does not extend through to such ends, I employ bars 12 of the form 45 illustrated in Fig. 3, which differ from the above described matrix bars 3 in that the recesses 13 formed on their under faces are not so deep as recesses 7 and of course do not bear matrices. Such recesses are, however, 50 of a sufficient depth to render continuous the overhanging or enlarged portion 9 of the slug, as will clearly appear from a reference to Fig. 4, in which a slug formed by bars of the kind herein described is shown in perspective, although the overhang or "head" 55 of the slug is obviously not so thick vertically at the space point in question as where characters are found on this upper face. Closure of the respective ends of the space 60 above the upper face of the mold 1 that is laterally inclosed by the walls of the recesses 7 or 13, as the case may be, in the assembled bars, is effected by means of blank bars 14 (see Fig. 8), or equivalent members.

65 The object in reducing the thickness of

the head 9 at space points in the fashion just described and illustrated in aforesaid Fig. 4, is to avoid contact between the so called "quad line" and the sheet being printed, when the type bar is in use, for such 70 contact will, of course, tend to smudge or smear the impression. In other words, such quad line lies with its front edge below the base line of the printing characters, that is below the base line of the relief base or 75 pedestal.

By the mechanism just described I am enabled to cast slugs or lines of type having enlarged upper portions with practically the same facility that ordinary slugs are cast in 80 the regular operation of the typograph. As will be obvious, the slugs formed in this fashion will excel in durability, as well as in the clearness of the impression which they are capable of giving, by reason of the 85 solid support afforded the characters on their faces. It has already been indicated that the casting mechanism may be variously arranged, while still maintaining the advantageous features of the improved matrix 90 bar construction constituting the present invention. There is, in other words, no intention, by referring, as above, to a particular typograph, to imply a limitation in the adaptability of the mechanism; and it 95 should further be borne in mind that such improved bars may be supported directly on the mold face under certain conditions, inasmuch as in the actual casting operation the bars are in effect simply clamped between such face and the under side of the 100 presser foot, or equivalent clamp member.

Instead of positioning the assembled body of matrix bars symmetrically over the slot in the mold, as is illustrated in Fig. 1, such 105 bars, together with their holder, may be shifted to one side or the other as shown in Fig. 6. In this way the form of the slug made from the composite matrix so provided is changed from that of Fig. 5 to that 110 of Fig. 7. The offsetting of the enlarged, type-bearing portions of the slugs thus obtained may be found desirable under certain conditions, and it is entirely feasible to thus form said slugs owing to the relatively large volume of the portion in question, whereas to attempt to do this by slightly overlapping the simple matrix would be entirely impracticable, owing to the chilling of the thin body of metal provided for.

Furthermore, by using bars without any recesses at all, the corresponding section of the slug will, of course, be reduced to simply the relatively narrow body portion. The 125 use of such bars and the formation thereby of slugs reduced at one or both ends is occasionally found desirable where a line of large type of greater length than the width of a column is being set up; for in such case 130

it may happen that the space left in a slug for one column will be just a trifle too small to accommodate a letter, as for example a "W," while to shift such letter to the next 5 succeeding slug would leave too large a blank space in the word being composed.

This and similar difficulties may be readily overcome with the improved construction of typograph mechanism under consideration.

10 Thus in the particular case under consideration, the upper, type-bearing portion of the first slug will be extended beyond the body of said slug by allowing the last bar, that carries the matrix of the letter "W" in the assumed instance, to overlap the face of the mold as shown in Fig. 8, thus leaving the end of said slug of the form clearly illustrated at the left in Fig. 10. Due note is, of course, taken of the length of the added or 15 projecting portion of the slug, and in assembling the bars for the next slug, the first bar 15 is a blank of a width equal to the extra space taken by such end matrix bar in forming the preceding composite matrix, 20 (see Fig. 9); as a result, when the slug is cast, the enlarged portion 9 thereof will terminate short of such end a distance equal to the projection on the preceding slug, as illustrated at the right in Fig. 10. When 25 the two slugs are assembled, accordingly, a continuous effect is secured that would be otherwise impossible.

It will be observed that in all the different forms of slug obtainable by the mechanism herein-before described, while the body of the slug remains of ordinary dimensions in length and width, that is of the same dimensions as it would have were it to bear type characters of regular size, such body is of 30 less than ordinary height by the thickness of the enlarged, or overhanging, portion 9. In this way, the slug may be maintained of standard height, which in the U. S. is 0.918 inches, as is well known. No additional 35 metal is obviously necessary in composing a body of display matter with slugs thus formed, over what would be required in the case of an equal body of ordinary print.

It will further be observed that by making 40 the overhanging enlarged portion of the slug of substantially the same thickness vertically as the body portion is transversely, the use of the supplemental blanks shown in Figs. 5 and 7 is not needed in order to support such overhang, but merely to fill in between the sides of the slug bodies, so that the latter can be properly locked in the form. In other words, in view of the fact that this 45 overhanging portion in the present improved slug is sufficiently thick vertically to render the same substantially inflexible, it is not necessary that the intermediate blank support-slugs should be of exactly the right height to accurately support the overhang 50 and thus the printing face of the slug. In

fact it is entirely permissible to utilize wooden spacing material for this purpose, this being desirable inasmuch as the weight of the form is thereby considerably reduced.

Other modes of applying the principle of my invention may be employed instead of the one explained, change being made as regards the mechanism herein disclosed, provided the means stated by any of the following claims or the equivalent of such stated means be employed:

I therefore particularly point out and distinctly claim as my invention:—

1. A slug or type-bar made from a composite matrix having its upper, type-bearing portion project beyond one end of said slug.

2. The combination of two slugs or type bars made from composite matrices and forming adjacent portions of a continuous line of type, the upper, type-bearing portion of one slug terminating short of the end of said slug adjacent to the other slug and such upper, type-bearing portion of the latter slug projecting a corresponding amount.

3. A slug or type-bar made from a composite matrix, said slug comprising a body portion of ordinary length and width, and an upper, enlarged portion bearing the type characters, such enlarged portion being vertically less thick at space points than where characters are thus formed on its face.

4. A slug or type-bar made from a composite matrix, said slug comprising a body portion of ordinary length and width, and an upper, enlarged portion bearing the type characters, such upper, enlarged portion terminating short of one end of said slug.

5. A slug or type-bar made from a composite matrix, said slug comprising a body portion of ordinary length and width, and an upper, enlarged portion bearing the type characters, such upper, enlarged portion projecting beyond one end of said slug.

6. The combination of two slugs or type-bars made from composite matrices and forming adjacent portions of a continuous line of type, each slug comprising a body portion of ordinary length and width, and an upper, enlarged portion bearing the type characters, such upper, enlarged portion of one slug terminating short of the end of said slug adjacent to the other slug and such upper, enlarged portion of the latter projecting a corresponding amount.

7. A slug or type-bar comprising a body portion of ordinary length and width, and an upper, enlarged portion bearing the type characters and laterally overhanging said body portion, such upper portion being sufficiently thick vertically to render substantially inflexible the part thereof thus overhanging.

8. A slug or type-bar comprising a body portion of ordinary length and width, and an upper, enlarged portion bearing the type

- characters and laterally overhanging said body portion, such upper portion being of substantially the same thickness vertically as said body portion is transversely.
- 5 9. A slug or type-bar comprising a body portion of ordinary length and width, and an upper, enlarged portion bearing the type characters and laterally overhanging said body portion, such upper portion being sufficiently thick vertically to render substantially inflexible the part thereof thus overhanging, and being less thick at space points than where characters are thus formed on its face.
- 10 10. A slug or type-bar comprising a body portion of ordinary length and width, and an upper, enlarged portion, bearing the type characters and laterally overhanging said body portion, such upper portion being of substantially the same thickness vertically as said body portion is transversely, and being less thick at space points than where characters are thus formed on its face.
- 20 11. A linotype slug of the character designated formed with type high surface printing characters, said printing characters being supported on a pedestal, with the quad line front edge below the base line of said printing characters and below the base line of the pedestal so as to prevent the contact 25 of said quad line edge with ink roller or surface to be printed upon, as set forth.
- 25 30

Signed by me this 2nd day of July, 1914.
